UNITED STATES PATENT OFFICE.

CHARLES D. SEEBERGER, OF NEW YORK, N. Y.

CONVEYER.

1,071,529.

Specification of Letters Patent. Patented Aug. 26, 1913.

Application filed December 19, 1910, Serial No. 598,072. Renewed January 25, 1913. Serial No. 744,243.

To all whom it may concern:

Be it known that I, CHARLES D. SEEBERGER, a citizen of the United States, residing at New York, in the county of New

5 York and State of New York, have invented certain new and useful Improvements in Conveyers, of which the following is a specification, reference being had therein to the accompanying drawing.

10 This invention provides an endless conveyer or carrier comprising a series of connected and moving sections to transport passengers or freight from one floor or level to another which assume a step-like character 15 or formation on the inclined portion of the carrying run between the floors and provide entrance and exit platforms of unbroken continuity curved with reference to a horizontal plane at the landings of the different 20 floors or levels.

The main object of this invention is to provide or afford greater ease of access to and exit from a moving carrier at the floors or levels connected by a carrying run there- 25 of, especially in the case of freight which may then be easily pushed upon or from the moving carrier.

30 The invention consists in the arrangements and organizations of parts hereinafter particularly described and then stated in the appended claims.

In the accompanying drawings which illustrate an embodiment of the several features of the present invention: Figure 1 is 35 a side view, diagrammatic in character, of a traveling carrier or conveyer illustrating an application of my present invention; Fig. 2 is a similar view upon an enlarged scale of certain parts shown in Fig. 1, illus- 40 trating more particularly the platform at the upper landing; Fig. 3 is a plan view of the platform-section of Fig. 2; Fig. 4 is a view similar to Fig. 1 upon an enlarged scale illustrating more particularly the plat- 45 form at the lower landing, and Fig. 5 is a plan view of the platform-sections of Fig. 4.

Referring to the drawings the numeral 10 indicates a series of sections, preferably in the form of steps each consisting of a 50 suitable tread and riser supported upon a suitable frame provided with a wheel 11 or some equivalent support such for example as a sliding shoe or runner, mounted on the ends thereof and traveling on suitable tracks 55 12, and having their axles suitably connected

together by rack-links 13 to which power is applied by means of a suitable drive wheel or sprocket 14 for imparting motion to the sections.

The conveyer or carrier is adapted to 60 travel upon upper and lower ways, each provided with tracks for the step-supporting wheels extending on inclines between the different levels or floors 15 and 16 and upon suitable curves adjacent the floors, the tracks 65 being so arranged with relation to the carrying wheels that the step or sections are in step-like formation on the incline and with their tread-surfaces in a continuous curve at each landing. In the form shown the 70 carrier is adapted to transport between an upper and a lower landing, and it is of course understood that when it is adapted to transport between more than two levels or landings the tracks will be correspond- 75 ingly extended. At the upper level the tracks of the carrying run extend in a curve whose highest point is at the front end of the upper platform formed by the treads and approximately under the associated 80 landing 15, and at the lower level the tracks for the carrying run extend in a curve whose lowest point is at the rear end of the lower platform formed by the treads and approxi- 85 mately under the associated landing 16. The 90 curved tracks for the upper landing merge into the inclined tracks, and the latter merge into the curved tracks for the lower landing so as to form a continuous upper way between the landings, and the tracks prefer- 95 ably also are curved at the ends and continue around and along the lower way to afford a continuous circuit. The present illustration shows the arrangement for a downwardly traveling carrier and which 95 would be reversed for an upwardly traveling carrier.

The links 13 connecting the axles of the steps or sections are divided and each is in the form of a toggle. The joint of each 100 link is provided with a depending arm 17 having an offset 18 at its free end engaging a guide 19 around the circuit, these arms controlling the relation of the sections or steps. The distance between the axles of 105 adjacent steps is of course greatest on the straight-away run on the incline and decreases when the steps are on a curve, and hence the links are made flexible so that they may break-down at the curves and 110

thus automatically lengthen or shorten under various requirements of operation on the runs. The guide 19 at the landings is spaced farther away from the tracks than it is on the inclined carrying portion of the run, so that the arms 17 are drawn down as the sections pass over the landing-tracks to break-down the links so that the nosings of the steps or sections may abut without gaps, and when the sections pass to the inclined portion of the run the links may straighten out to accommodate the increased separation between the step-axles.

From the foregoing disclosure it will be seen that the initial tread at the top and the last tread at the bottom are practically in line with the floor plates 15 and 16 respectively, and that all the tread surfaces comprising either the entrance or the exit platform as at Figs. 3 and 5, respectively, are in a continuous curve, the contiguous nosings of adjacent steps or sections being there together without gaps on the same line and are not stepped-up with reference to each other as would be the case if the existing type of elevator or carrier composed of similar sections traversed tracks curved at the landings. The platform at the entrance curves away from the landing 15, and at the exit curves toward the landing 16, so that greater ease of access and exit is afforded and freight may easily be pushed on or off the carrying run.

I claim:

1. In a device of the class described, a continuous series of carrying sections moving between different levels, and means to curve the sections forming the platform at the upper level in the direction of their travel without gaps.

2. In a device of the class described, a continuous series of carrying sections moving between different levels, and means to curve the sections forming the platform at the lower level in the direction of their travel without gaps.

3. In a device of the class described, a continuous series of carrying sections moving between different levels, and means to curve the sections forming the platforms at the upper and lower levels in the direction of their travel without gaps.

4. In a device of the class described, a pair of tracks providing an inclined run and the necessary end-curves to make a complete circuit, an endless series of sections each provided with supports coöperating with said tracks, a system of links connecting said sections, and means to move the sections, the tracks for the sections forming the upper platform being curved with reference to a horizontal plane in the direction of the travel of the sections.

5. In a device of the class described, a pair of tracks providing an inclined run

and the necessary end-curves to make a complete circuit, an endless series of sections each provided with supports coöperating with said tracks, a system of links connecting said sections, and means to move the sections, the tracks for the sections forming the lower platform being curved with reference to a horizontal plane in the direction of the travel of the sections.

6. In a device of the class described, a pair of tracks providing an inclined run and the necessary end-curves to make a complete circuit, an endless series of sections each provided with supports coöperating with said tracks, a system of links connecting said sections, and means to move the sections, the tracks for the sections forming the upper and lower platform being curved with reference to a horizontal plane in the direction of the travel of the sections.

7. In a device of the class described, a pair of tracks providing an inclined carrying run and the necessary end-curves to make a complete circuit, an endless series of sections each provided with supports coöperating with said tracks, a system of flexible links connecting said sections, means to move the sections on the tracks, and means to flex the links at the upper landing, the track being arranged to curve the sections forming the platform at the upper landing with reference to a horizontal plane.

8. In a device of the class described, a pair of tracks providing an inclined carrying run and the necessary end-curves to make a complete circuit, an endless series of sections each provided with supports coöperating with said tracks, a system of flexible links connecting said sections, means to move the sections on the tracks, and means to flex the links at the lower landing, the track being arranged to curve the sections forming the platform at the lower landing with reference to a horizontal plane.

9. In a device of the class described, a pair of tracks providing an inclined carrying run and the necessary end-curves to make a complete circuit, of a series of sections each provided with supports coöperating with said tracks, a system of flexible links connecting said sections, means to move the sections on the tracks, and means to flex the links at the landings, the tracks being arranged to curve the sections forming the landings with reference to a horizontal plane.

10. In a device of the class described, a pair of tracks providing an inclined carrying run and the necessary end-curves to make a complete circuit, an endless series of sections each provided with supports coöperating with said tracks, a system of toggle links connecting said sections, means to move the sections, the tracks at the upper landing being curved away from said

landing with reference to a horizontal plane, an arm on each link, and a guide for the arm.

11. In a device of the class described, a pair of tracks providing an inclined carrying run and the necessary end-curves to make a complete circuit, an endless series of sections each provided with supports co-operating with said tracks, a system of toggle links connecting said sections, means to move the sections, the tracks at the lower landing being curved toward said landing with reference to a horizontal plane, an arm on each link, and a guide for the arm.
12. In a device of the class described, a pair of tracks providing an inclined carrying run and the necessary end-curves to make a completed circuit, an endless series of sections each provided with supports co-operating with said tracks, a system of toggle links connecting said sections, means to move the sections, the tracks at the landings being curved with reference to a horizontal plane in the direction of the travel of the sections, an arm on each link, and a guide for the arm.
13. In a device of the class described, a pair of tracks providing an inclined carrying run and the necessary end-curves to make a complete circuit, an endless series of sections each provided with supports co-operating with said tracks, a system of toggle links connecting said sections, means to move the sections, the tracks at the upper

landing being curved with reference to a horizontal plane, an arm depending from each link and having an offset portion, and a guide for the offsets.

14. In a device of the class described, a pair of tracks providing an inclined carrying run and the necessary end-curves to make a complete circuit, an endless series of sections each provided with supports co-operating with said tracks, a system of toggle links connecting said sections, means to move the sections, the tracks at the lower landing being curved with reference to a horizontal plane, an arm depending from each link and having an offset portion, and a guide for the offsets.

15. In a device of the class described, a pair of tracks providing an inclined carrying run and the necessary end-curves to make a complete circuit, an endless series of sections each provided with supports co-operating with said tracks, a system of toggle links connecting said sections, means to move the sections, the tracks at the upper and lower landings being curved with reference to a horizontal plane, an arm depending from each link and having an offset portion, and a guide for the offsets.

In testimony whereof I affix my signature in presence of two witnesses.
